THERMOSTATIC DEVICE

Ralph W. De Lancey, Meriden, Conn., assignor to
 The Miller Company, Meriden, Conn., a corporation of Connecticut

Application June 22, 1945, Serial No. 601,014

1 Claim. (Cl. 200—139)

1

The present invention relates to thermostatic devices, and is more particularly directed toward thermostatic devices of the type employing spiral bimetal thermostats for actuating the contacts of a control circuit.

The present invention is suitable for use in connection with astatats and aquastats used in the control of oil burners and stokers and having manual means for presetting the device to control the circuit at selected temperatures of the medium surrounding the thermal element.

The present invention contemplates a convenient worm and worm wheel arrangement for adjusting the thermostat and the provision with such worm and worm wheel arrangement of a simple indicator whereby the adjustment may be ascertained.

The accompanying drawings show, for purposes of illustrating the present invention, an embodiment in which the invention may take form, it being understood that the drawings are illustrative of the invention rather than limiting the same.

In these drawings:

Figure 1 is a perspective view of the complete device;

Figure 2 is an elevational view showing the circuit open and the parts in position for low temperature control;

Figure 3 is a view similar to Figure 2 showing the parts in position for high temperature control;

Figure 4 is a sectional view on the line 4—4 of Figure 2;

Figure 5 is a sectional view on the line 5—5 of Figure 2; and

Figure 6 is a sectional view on the line 6—6 of Figure 5.

A sheet metal plate 10 forms the frame element for the entire device. A coupling or bushing 11 secured to the plate is provided for securing the entire device to a boiler or other structure where temperature conditions are to be employed for controlling a circuit.

The bushing 11 is counterbored to receive an arbor 12. This arbor is secured to the upper end of a spiral bimetallic thermostat as indicated at 13. The lower end of the thermostat is secured to a rod or shaft 14 which extends up through the arbor 12. This rod carries an arm 15 on which is mounted an insulated contact 16. The plate 10 carries a terminal block 17 provided with a contact 18 opposite the contact 16.

A subframe 19 is apertured at 20 to fit about the arbor 12 and is held in place by a screw 21

which also forms a stop for the arm 15. The arbor 12 fixedly carries a worm wheel 22. The subframe 19 carries a worm 23 in mesh with the worm wheel 22. The worm 23 is anchored in place by a spring 23' which presses it to the left. An operating knob 24 is carried outside a front flange 25 formed on the plate 10. Turning the knob 24 makes it possible to adjust the tension of the bimetal thermostat and determine the temperature at which sufficient expansion in the bimetallic element will occur to cause the contacts 16 and 18 to meet. While the drawing shows a thermostat of the normally open circuit type, it will be understood that the invention is equally well adapted for use with normally-closed-circuit devices.

The worm 23 carries a nut 26 which is adapted to travel along the worm. When the device is first assembled this nut is loosely received in an opening 27 in an indicator 28. The lower end of the indicator rides along the subframe 19 and may extend down into a slot 29 as shown.

When the factory adjustment of the device is made, the contact arm is given a predetermined loading, and the parts are brought to the proper position to have the circuit closed (or opened) at the desired temperature. The nut 26 can then be moved freely along the shaft to the position desired for the indicator 28 and the indicator soldered to it. Thereafter the indicator 28 will prevent turning of the nut and will move back and forth as the adjustment is made. The device is provided with a cover 30 having a slot 31 through which the indicator 28 may be observed.

Since it is obvious that the invention may be embodied in other forms and constructions within the scope of the claim, I wish it to be understood that the particular form shown is but one of these forms, and various modifications and changes being possible, I do not otherwise limit myself in any way with respect thereto.

What is claimed is:

A temperature responsive circuit controller comprising a supporting plate, a mounting bushing secured rearwardly of the plate, an arbor mounted in the bushing, a thermal motor carried by the arbor and including a shaft extending through the arbor and movable about its axis, a contact arm carried by the shaft, a fixed contact cooperable with the arm, a worm wheel carried by the arbor, the supporting plate having a forwardly extending bracket, apertured to one side of the shaft axis, a subframe secured to the plate and having a front opening in line with

the aperture and a rear aligned aperture smaller than the other apertures, a worm insertable through the larger apertures and having an end portion receivable in the smaller aperture, the worm being in mesh with the worm wheel, and a spring anchoring the worm in place, the worm being rotatable to vary the tension applied to the thermal motor.
